HANGING BRACKET FOR ILLUMINATING
TUBES

Elwood Wiles, Portland, Oreg.

Application June 26, 1950, Serial No. 170,397

3 Claims. (Cl. 240—51.12)

1

This invention relates to brackets and is particularly adapted to be used in connection with fluorescent lighting fixtures.

The primary object of the invention is to provide a bracket for supporting the weight of the fluorescent tubes extending beyond the light fixtures.

Heretofore, the fluorescent tubes were supported from the ceiling beyond the fixture, but with my new and improved supporting bracket the fixture itself supports the weight of the fluorescent tube through my bracket, making a very neat and substantial arrangement.

These and other incidental objects will be apparent in the specification, drawings and claims.

Referring to the drawings:

Figure 1 is a perspective underneath view of a fluorescent fixture and tube, including my new and improved bracket for supporting the tube.

Figure 2 is a side view of the fixture, partially broken away, illustrating how my new and improved bracket is applied and associated therewith.

Figure 3 is a perspective view of my new and improved bracket removed from the fixture and tube.

Figure 4 is a perspective view of the light fixture, partially broken away, illustrating how the fluorescent tube is mounted to the fixture and how the brackets support the tube to the fixture.

Referring more specifically to the drawings:

I will first describe the general arrangement of a fluorescent light fixture, which consists of a base plate 1, which is secured to the ceiling 2 by way of the screws 3. Secured to the underside of the base plate 1 is the fixture frame 4, in which is mounted the transformer 5, and to which the fluorescent tube socket 6 is secured by way of the holding screw 7. The fixture has a cover 8 secured to the same by any suitable fastening means, as for instance the screws 9.

My new and improved bracket consists of a single wire 10, formed in the shape of a U at 11, having the loops 12 bent downwardly therefrom at approximately right angles, the said loops terminating in the legs 13, extending upwardly at an acute angle to the U-shaped portions 11, the ends being bent inwardly at right angles at 14. Resilient covering 15 surrounds a portion of the loops 12 and are for the purpose of preventing the bracket from sliding upon the fluorescent tubes, which the said bracket is supporting.

In order to install the bracket, the right angle bends 14 are inserted through the holes 16 of

2

the frame 4 of the light fixture. This may be done when the fixture is installed, or after the fixture is installed, as the bracket can be distorted sufficiently to force the bends 14 into the holes, after which the said bends prevent the legs 13 from coming back through the holes 16 of the fixture 4.

The fluorescent tubes 17 have well known terminals 18 adapted to enter the electric sockets 19. This is already standard practice except that when using my bracket the ends of the tubes are entered through the loops 12 of the bracket then into the socket 6. The U-shaped portion 11 of the bracket will come to rest within and somewhat above center of the tubes as best illustrated in Figures 1, 2 and 4.

These brackets are precision manufactured and when installed as above described, they will hold the fluorescent tubes in a horizontal position, the end 19 of the U-shaped portion 11 bears snuggly against the end 20 of the light fixture cover 8, the U-shaped portion forming a compression member and the legs 13 forming tension members. The resilient member 15 prevents the tube from coming out of the socket 6 as may be caused by vibration or the like which exists in many installations. Therefore, my new and improved bracket not only supports the weight of fluorescent tubes from the light fixtures, but it prevents the tubes from coming out of their sockets due to vibration.

In the attaching of my new and improved bracket, I find that shaping the loops 12 so that the points 15A engage the tube 17 leaving a slight clearance between the bottom of the loop at 15B and the tube, prevents the slipping of the tube much more effectively than if the loop contacted the tube all the way around the resilient material 15.

The cover 8 is provided with notches 21 coinciding with the openings 16 so that said cover can be removed from the fixture without removing the legs 13 of the bracket from the frame 4 of the fixture, although the fluorescent tubes have to be removed before the said cover plate could be removed.

I do not wish to be limited to using my brackets on the particular form of fixture illustrated, as it is adapted to be used upon any shape of fixture having any number of fluorescent tubes extending therefrom.

Although certain specific embodiments of the invention have been shown and described, it is obvious that many modifications thereof are possible. The invention, therefore, is not to be re-

stricted except in so far as is necessitated by the prior art and by the spirit of the appended claims.

What I claim is:

1. A bracket for supporting fluorescent light tubes extending from lighting fixtures, comprising a single strand having its central portion bent into a U-shape with the branches thereof substantially parallel, the portions of said strand at the end of said branches being bent outwardly into depending loops disposed in planes perpendicular to said branches for receiving the tubes, the portions of said strand at the outer ends of said loops being bent to form hangers extending upwardly at an acute angle to the plane of the central U-shaped portion and having at their ends hanger means which are securable to the fixture, whereby the U-shaped portion will abut the fixture between the tubes with the depending loops supporting the tubes.

2. A bracket for supporting fluorescent light tubes extending from lighting fixtures, comprising a single strand having its central portion bent into a U-shape with the branches thereof substantially parallel, the portions of said strand at the end of said branches being bent outwardly into depending loops disposed in planes perpendicular to said branches for receiving the tubes, the portions of said strand at the outer ends of said loops being bent to form hangers extending upwardly at an acute angle to the plane of the central U-shaped portion and having at their ends hanger means which are securable to the fixture, whereby the U-shaped portion will abut the fixture between the tubes with the depending loops supporting the tubes, said loops being of a depth to substantially completely receive the tubes with the upper ends of said loops disposed adjacent the upper surfaces of the tubes to position the branches of the U-

shaped portion adjacent and substantially parallel with the upper inner sides of the tubes and with the hanger portions disposed above the tubes.

3. In a lighting fixture having a base portion enclosed by a cover and fluorescent light tubes extending from the base portion beyond the cover, a tube hanging bracket for said tubes comprising a formed single strand having its central portion bent into a U-shape with the branches thereof substantially parallel, the portions of said strand at the end of said branches being bent outwardly into depending loops disposed in planes perpendicular to said branches for receiving and partially surrounding the tubes, the portions of said strand at the outer ends of said loops being bent to form hangers extending upwardly at an acute angle to the plane of the central U-shaped portions and having at their ends hanger means, apertures in said fixture base portion for receiving said hanger means, and slots in said cover for passing said hangers, whereby the U-shaped portion will abut the fixture cover between the tubes with the depending loops supporting the tubes.
